UNITED STATES PATENT OFFICE

JAMES P. RATIGAN, OF LOS ANGELES, CALIFORNIA

SADDLE

Application filed October 8, 1928. Serial No. 311,147.

This invention relates to saddles of the type used, for example, to support the grip used on a polish rod in the pumping of oil wells.

Heretofore, saddles were of solid construction with a vertical bore through which the polish rod projected, the grip on the polish rod seating upon the upper face of the saddle. With this prior construction of saddle it was necessary to release the grip from the polish rod, support the polish rod from a point beneath the saddle by a suitable clamp and then lift the saddle off of the polish rod, these operations being necessary when it was desired to disconnect the walking beam from the polish rod for pulling the pump or for any other purpose that required the polish rod to be removed.

One of the objects of this invention is to eliminate some of the above mentioned operations, thus expediting the connecting and disconnecting of the polish rod with the walking beam.

Other objects and advantages will appear in the subjoined detailed description.

The accompanying drawings illustrate the invention.

Figure 1 is a side elevation of a saddle constructed in accordance with the provisions of this invention, cable socket eyes, a polish rod and a polish rod grip being also indicated in broken lines.

Figure 2 is a plan view of the saddle shown in Figure 1.

Figure 3 is a vertical section on the line indicated by 3-3 of Figure 1.

Referring to the drawings, there is provided a vertically slotted body 6, the slot being indicated at 7. The slot 7 is of a width to accommodate the polish rod which is indicated at A.

At its opposite ends the body 6, which is in the form of a cross bar, is provided with trunnions 8 which are circular in cross section so that said trunnions may be received within cable socket eyes which are indicated at B in Figure 1, said socket eyes constituting no portion of the present invention. Any suitable devices as, for example, those indicated at 9, may be used for preventing accidental dis-

engagement of the eyes B with the trunnions. The devices 9 illustrated constitute no portion of the present invention, but are the subject matter of my copending application filed October 3, 1928, Serial No. 310,118.

The front face 10, through which slot 7 opens, is substantially flat and fitting thereagainst is a shiftably mounted gate 11 which, when the same is in closed position, closes the upper portion of the slot 7. In this instance, the gate 11 is pivotally mounted, the pivot 12 thereof being a cap screw that is screwed into the body 6 to one side of the slot 7. The gate 11 may be opened by swinging it upwardly and to the left in Figure 1, and, when the gate is closed, the upper flat face 13 thereof is flush with the upper flat face 14 of the body. The grip C on the polish rod A is adapted to seat on the faces 13, 14 so that the saddle will support said grip. When said grip is so supported, it prevents the gate 11 from accidentally opening.

When the gate 11 is closed, it seats upon a pair of shoulders 14, one on each side of the slot 7, said shoulders being horizontal and projecting from the front of the body. The shoulders 14 are flat as is also the underface of the gate where it rests upon said shoulders.

Gravity, alone, may be depended upon to hold the gate 11 closed, in event of the grip unseating from the saddle, but it is preferable to provide a latch for positively holding the gate closed, for the reason that if the sucker rods should break, thus considerably diminishing the load on the engine that is operating the pump, the down strokes of the saddle might become so rapid that the grip C would not follow and there would thus be considerable friction occurring between the polish rod and the inner face of the gate and this friction would tend to open the gate and thus free the polish rod from the saddle. In this instance, the latch means, which is indicated at 15, is constructed as follows:

The latch member 15 is pivoted at 17 to the front face of the body 6, near the upper face thereof and said latch member is provided in its inner face with a recess 18 that accommodates a spring 19 and a fixed spring seat 20 which projects from the front face of the body

6 and against which one end of the spring 19 rests, the opposite end of said spring engaging that wall of the recess 18 that lies adjacent to the gate. Thus, the spring 19 urges the latch member 15 toward the gate or to the left in Figure 1, and said gate is provided with a shoulder 21 that projects beneath the latch member 15 when said latch member is in the latching position shown in Figure 1. Thus, 10 when the latch member is in the latching position, it overhangs the shoulder 21 so as to prevent upward swinging of the gate from closed position into open position. The pivot 17 affords one way of mounting the latch member so that said latch member will be in 15 sliding relation with the body 6. The latch member, as well as the gate, operates in a vertical plane.

It will be clear from the foregoing that the 20 invention operates as follows:

Assuming that the parts are in the positions shown in Figure 1 and that the polish rod is in the slot 7 and that the polish rod grip, clamped on said rod, rests upon the saddle, to 25 release the polish rod from the saddle, which, through the eyes B and the cables, not shown, is connected with the beam hanger, not shown, the polish rod will be raised by any suitable tackle sufficiently high to lift the grip C well 30 above the saddle and the latch member 16 will then be thrust to the right in Figure 1, thus releasing the gate, and the gate will be swung upwardly and to the left in Figure 1. The tackle supporting the polish rod will then be 35 operated to move the polish rod out of the slot 7.

To replace the polish rod in the saddle, it is only necessary to swing said polish rod into the slot and then swing the gate closed.

40 While the gate is being closed, the gate 11 will thrust against the sloping edge 22 of the latch member, thus swinging the latch member to the right until the shoulder 21 passes below the level of the bottom edge of the latch 45 member, whereupon said latch member will be moved by the spring 19 into its latching position over the shoulder 21.

I claim:

1. A saddle comprising a member provided 50 with a vertical slot in its front face, a member mounted to slide to and from closed position in front of said slot, a shoulder on the first mentioned member for the second mentioned member to rest on when in closed position, a 55 second shoulder on one of the members, and a latch member pivoted at its upper end to one of the members in position to normally overhang the second shoulder.

2. A saddle comprising a cross bar provided 60 with a vertical slot in its front face and with shoulders on opposite sides of the slot, a gate pivoted to the cross bar to swing in a vertical plane to and from closed position in front of the slot and resting on the shoulders, 65 the gate provided with a shoulder, and a latch

member pivoted to the cross bar to swing in a vertical plane to and from a latching position overhanging the shoulder on the gate.

3. A saddle comprising a cross bar provided 70 with a vertical slot in its front face and with shoulders on opposite sides of the slot, a gate pivoted to the cross bar to swing in a vertical plane to and from closed position in front of the slot and resting on the shoulders, 75 the gate provided with a shoulder, a latch member pivoted to the cross bar to swing in a vertical plane to and from a latching position overhanging the shoulder on the gate, and a spring yieldingly holding the latch member in the latching position.

4. A saddle comprising a member provided 80 with a vertical slot in its front face, another member movably connected with the first mentioned member operable in a vertical plane to and from closed position in front of 85 said slot, a shoulder on the first mentioned member for the second mentioned member to rest on when closed, a second shoulder on one of the members, and a latch member pivoted to the member not provided with the second 90 shoulder, said latch member and second shoulder being normally in superposed relation so as to prevent movement of the second mentioned member away from its closed position.

Signed at Los Angeles, California, this 24th 95 day of September, 1928.

JAMES P. RATIGAN.
